UNITED STATES PATENT OFFICE

123,512

DESIGN FOR A MULTIPLE ENVELOPE OR SIMILAR PACKAGE

Helen Tanis, Chicago, Ill.

Application February 26, 1940, Serial No. 90,528

Term of patent 7 years

To all whom it may concern:

Be it known that I, Helen Tanis, a citizen of the United States, residing at Chicago, in the county of Cook and State of Illinois, have invented a new, original, and ornamental Design for a Multiple Envelope or Similar Package, of which the following is a specification, reference being had to the accompanying drawing, forming part thereof.

Fig. 1 is a top plan view of a multiple envelope or similar package showing my new design. The circular portions are transparent and the vertical lines indicate a contrasting surface finish.

Figure 2 is the multiple envelope or similar package in expanded condition, as viewed from one of the longer sides.

Fig. 3 is a perspective view thereof.

I claim:

The ornamental design for a multiple envelope or similar package, as shown and described.

HELEN TANIS.
